UNITED STATES PATENT OFFICE.

ALEXANDER CRAWFORD CHENOWETH, OF NEW YORK, N. Y.

APPARATUS FOR MAKING AND LAYING PROTECTIVE CONCRETE COVERINGS.

1,187,503.

Specification of Letters Patent. Patented June 20, 1916.

Original application filed July 10, 1913, Serial No. 778,291. Divided and this application filed December 18, 1914. Serial No. 877,902.

To all whom it may concern:

Be it known that I, ALEXANDER CRAWFORD CHENOWETH, a citizen of the United States, residing in the city of New York, county and State of New York, have invented certain new and useful Improvements in Apparatus for Making and Laying Protective Concrete Coverings, of which the following is a specification.

10 My invention relates to concrete or cement construction and it refers to apparatus for making and depositing reinforced slabs in the places where they are laid, such for instance as river beds, embankments, levees, irrigation ditches, roads and the like, in order to protect the surface at such points against the erosion caused by floods and the action of the river.

The present application is a division of 20 my application for Letters Patent filed July 10, 1913, Serial No. 778,291.

I have illustrated types of my invention in the accompanying drawings, wherein;

Figure 1 is a view in cross-section of a 25 portion of one of my improved reinforced protective slabs, the section being taken in a plane at right angles to the ridges formed in the reinforcing device. Fig. 2 is a similar view to that of Fig. 1, but with the 30 plane of the section taken through the slab at right angles to that shown in Fig. 1. Fig. 3 is a perspective view of a portion of my improved reinforcing device or fabric. In this construction the mesh of the reinforcing netting is triangular shaped and the 35 ridges or elevations are parallel with each other. Fig. 4 is a perspective view on a reduced scale of a portion of a river, and shows the river bank and bed as covered 40 with my improved reinforced revetment, and with a portion of the revetment which lies out of the water, broken away, in order to show the particular location of the reinforcing fabric or netting. Fig. 5 is a similar 45 view to that shown in Fig. 4, but with the ridges in the reinforcing wire-netting arranged diagonally instead of running substantially at right angles to the slope of the ground. Fig. 6 is an enlarged cross-sec- 50 tional view of the slabs shown in Fig. 4, and in which the mesh of the netting is shown as rectangular shaped. Fig. 7 is a 55 perspective view of a portion of a river showing a float or platform upon which has been made one of my improved reinforced

slabs, which, in plastic condition, is to be removed from the float and placed in position on the river bed beneath the water. The right hand end of the reinforced slab shown in this view has projecting from the 60 edge thereof, the end of the reinforcing sheet of wire-netting, and the lower right hand corner of the slab is partly broken away. Fig. 8 is an enlarged perspective view of a portion of the reinforcing slab shown in 65 Fig. 7, and with one edge broken away. Fig. 9 is a perspective view of a portion of a river, and shows the bank above the water line as lined with the protective reinforced slabs of material and with a protective slab being dropped from the float on which it has been made, into position in the water, and with a fresh section of the reinforcing netting connected with one end of the plastic slab in the operation of building an extension of the slab to increase its 70 length. Fig. 10 is a perspective view of a portion of a river showing a temporary platform rigged in operative position upon the exposed portion of the bank and overhanging the water, and on which platform has been made one of my improved reinforced protective sections, prior to transferring the same from the platform to the bed of the river beneath the water. 75

Referring to the drawings, in which like numbers of reference designate like parts throughout, 1 indicates the embankment or levee of a river, 2 the bed and 3 the water in the river. The embankment 1, is continuously covered over a sufficiently wide area with a series of protective reinforced sections or slabs 4, while a corresponding portion of the river bed 2, immediately adjoining the bank at the water line is likewise covered 80 with a series of the connected protective slabs 5, thereby providing a substantially unbroken smooth protective coating for the earth at the places specified. This protective coating is installed by constructing the 85 slabs or coverings one at a time, those which cover the exposed river bank may be made directly upon the ground by first cleaning the ground and properly sloping and grading it, and then placing directly upon it a 90 suitably shaped sheet of steel wire-netting 6, which is formed with parallel bends or ridges 7, which in the preferred form run substantially at right angles to the slope of the ground as indicated herein. After the 95

85

90

95

100

105

110

bent wire-netting is placed in position directly on the ground, concrete 8, is then placed upon it in plastic condition, so as to fill all of the cavities formed by the bends 5 upon the upper and lower sides of the netting, the thickness of the layer required being previously determined by the aggregate height of the bends upon opposite sides of the neutral axis. The concrete is then 10 rammed and tamped to make it compact and to even its surface, and it is then left to harden. By this construction, the crimped and deformed wire-netting is completely embedded in the concrete and the particular 15 shape of the netting brings each of the wires into its proper relative position each side of the neutral axis, so as to give the best reinforcement, each wire becoming either a compression member or a tension member. In 20 addition to the bent wire serving as a truss within the body of concrete, it also acts as a receptacle or form by means of which the plastic concrete, when placed upon the wire-netting, is retained in place and may set or 25 harden without becoming displaced, even though the construction of the reinforced section takes place upon steep inclines of ground. I prefer to have the ridges 7, extend in a direction substantially at right angles to the slope, and as indicated in several 30 of the figures, but the ridges may run in a diagonal direction if preferred.

In placing the protective sections 4, upon the bank, as soon as one has been completed, 35 the adjoining one is begun by placing a sheet of wire-netting 6, on the ground immediately adjoining the last made section, so as to bring the abutting edges of the sheets of wire-netting together, and if preferred, they 40 may be fastened together in any well known manner, or overlapped, so that when the concrete is packed upon the freshly laid sheet of wire-netting it may be made to cover the joint between the adjoining sheets 45 of the wire-netting. In this way a continuous and unbroken lining is formed directly upon the river bank, and the slight flexibility of the wire-netting in one direction, namely, in the direction at right angles to the line of direction of the ridges, serves to 50 readily permit the body of concrete, together with the reinforcing sheet to conform to the shape of the ground upon which the reinforced slab is built.

55 In order to prevent the slab 4, from sliding downwardly out of place, I attach to the upper end of each cables 9, which are in turn secured to the anchorages 10, placed in the ground.

60 The protective reinforced slab 5, which is placed upon the river bed beneath the water is constructed in the same manner as the slab 4, already described, in so far as the wire-netting and the concrete is concerned. It is, 65 however, provided with an exterior cover of

textile fabric in order to protect the concrete while in plastic condition, from the action of the water in which the slab is deposited, and until the concrete hardens. These slabs 5, are each provided with a reinforcing sheet 70 of bent or deformed wire-netting 11, the same as the wire-netting 6, previously described. In making this slab, a series of strips 12, such for instance as willow boughs, are first placed in parallel order upon the 75 flexible metallic apron 13, which rests upon a platform or float 14, and over these strips is laid a piece of textile fabric 15, such for instance as burlap. Then the sheet of bent wire-netting 11, is placed upon the fabric, 80 and a series of tie-wires 16, are secured to the flexible strips 12, on the bottom and are brought up through the fabric and through the wire-netting and are so positioned as to extend through the body of concrete subsequently placed upon the wire-netting. The concrete 17, is then placed upon the wire-netting and is packed down into a solid body so as to completely embed the netting, except one end thereof which is left free as at 18, (see Fig. 7). The fabric 15, is then folded 90 around the sides and over upon the top of the concrete body so as to completely envelop it. Cross-bars 19, of flexible material are then placed upon the fabric 15, and the tie-wires 16, which are brought up through the concrete and fabric, are secured to the crossing points of the flexible strips 19.

Suitable cables 20 and 21, extending at 100 right angles to each other, are incorporated in the body of the slab as it is built up and the ends of these cables protrude at the edges of the slab in pairs as indicated in Fig. 7. These cables may be used for the purpose of dragging the slab into position, and also for the purpose of anchoring it, as well as tying it to the adjacent edges of the abutting slabs. The fabric 15, prevents the water from washing away the cemental material of the slab while in plastic 110 condition and keeps the slab in shape. The strips 12 and 19, hold the fabric in place and also protect the plastic material when the slab is slid on the apron.

The projecting edge 18, of the bent wire-netting is utilized for connecting the sheets of wire-netting with a similar sheet of the netting of the adjacent slab lying above on the bank of the river, as indicated in Figs. 4, 5 and 9, wherein the extension 18, of the slab which is placed upon the river bed, is interlocked with the lower end of the wire-netting of one of the slabs 4, which is subsequently built up upon the sloping ground above the water level.

120 The flexible apron 13, upon which the slab 5, is constructed, is made of a suitable metal and with sufficient flexibility to readily bend under the weight of the superimposed slab when the apron with the slab 130

upon it is drawn off of the float 14. The outer end of the apron 13, is provided with perforations 22, for the reception of a hook 45, to which is connected a cable 46, running 5 to the shore where it is operated by a windlass 47, secured to the ground. By this means the apron with its burden may be drawn off the float when pulled upon, and I provide the deck of the float with suitable 10 rollers 23, arranged in the surface thereof and over which the apron may be moved. I also provide at each side of the line of movement of the apron 13, a row of vertical rollers 24, which keep the apron in place as it 15 is slid off the float and guides it in its movement.

After the slab 5, is formed upon the apron 13, on the float and is to be launched and dropped into its proper position on the bed 20 of the river, the float is drawn up toward the bank with the forward end of the newly formed slab nearest the bank, whereupon the apron is engaged by the hook 45, and drawn upon, and as it leaves the float it is 25 directed on to the bed of the river near the water line so that its forward end rests upon the bed at about the point of the water line. With the end of the apron held fast at this point on the bank, the float is then drawn 30 gradually away from the bank by means of suitable cables 26, as indicated in Fig. 9 and the weight of the slab bends the apron gradually downwardly on to the bed of the river. When the float has been withdrawn from 35 beneath the greater part of the apron, so as to leave one end still upon the float, the relative movement of the two terminates, and then the float with the apron move together so that the apron is gradually withdrawn 40 from beneath the plastic slab, which finally comes to rest in the dotted line position indicated in Fig. 9. This slab being then in plastic condition, readily conforms to the contour of the surface of the river bed, and 45 its jacket of textile fabric protects the material of the slab from the water until such material has hardened. When the slab is thus deposited upon the river bed, the apron 50 13, is drawn upon the deck of the float by means of cables 27 and 28, which are connected with the winding-shaft 29, which is mounted upon one end of the float and is provided at its opposite ends with suitable hand-operated gearing 30 and 31, for winding 55 the cable upon the shaft.

In cases where it is necessary to make the slabs 5, of greater length than can be accommodated by the particular float and apron in use, I first build one of the slabs 5, and 60 start to launch it into position, as indicated in Fig. 9 and when the apron 13, has been partly withdrawn from beneath the completed slab, I stop the operation and place upon the exposed part of the apron a new 65 section of bent wire-netting 32, and connect

its forward end with the rear end of the wire-netting contained in the newly formed slab. I then fill in the concrete on the new section of wire-netting and complete it, whereupon the withdrawal of the apron 70 from beneath the slab is proceeded with.

By virtue of the flexible apron 13, being projected into the water with the plastic slab upon it, the slab itself is prevented from bending or breaking as might otherwise be 75 the case, though of course these slabs may be launched without the use of the apron. I, however, prefer to use the apron, as it provides a safe means of depositing the plastic slab upon the river bed, and at the 80 same time enables me to lengthen the slab in cases where it is necessary, as above stated.

It will be noted that the bent wire-netting, in addition to acting as a reinforcing 85 trussing member, also acts to hold the concrete in place while plastic and until it hardens, thereby insuring a perfect reinforcing covering for the surface upon which the slab is deposited. 90

In a reinforced concrete slab in which the reinforcing element lies in the plane of the midsection or neutral axis, such reinforcing element is subjected to bending moments and accordingly it possesses comparatively little 95 strength in resisting strains or stress. It will be noted, that in my improved construction, I incorporate the reinforcing element in the slab in such a position relative to the neutral axis that it is free from 100 bending moments and becomes a compression or tension element, or both, thereby providing increased reinforcing strength.

The wire-netting shown in several of the figures has a rectangular shaped mesh, but 105 in the form shown in Figs. 1, 2 and 3, the mesh is of a well known triangular shape. This steel wire-netting having the triangular mesh provides a very strong trussing structure when incorporated in the body of 110 concrete, and it of course acts as a receptacle or form in retaining the plastic concrete in place during the hardening process. This particular wire mesh is a well known commodity on the market and I prefer to 115 use it in many cases.

In using wire-netting either of a triangular or rectangular mesh, I bend the netting into a series of parallel ridges, each of which consists of a short vertical member or 120 leg 7^b and a long oblique leg 7^a, and preferably the oblique member is approximately three times the length of the vertical or short member. For example, if the short leg is four inches, the long one is twelve, 125 and in using such a proportion with a triangular mesh netting, the mesh is an equilateral triangle having its sides about four inches long. The short leg is normal to the upper and under surfaces of the slab and it 130

accordingly serves as an effective barrier or retainer for the plastic material as well as a reinforcing element when the plastic material has hardened. This short leg or stretch is also used as a gage by means of which the thickness of the completed slab may be predetermined, the plastic cemental material being made to cover both the upper and lower ends of the short leg to a slight degree, or if preferred, the ends of the short leg may be made flush with the surfaces of the slab or permitted to project a slight distance above such surfaces. The long leg extending diagonally from the upper end of one short leg to the lower end of the adjacent short leg provides a highly efficient reinforcing element. The bends in the netting herein shown are symmetrical and they are alike upon each side of the neutral axis.

In Fig. 10 I show apparatus by means of which the plastic slab 5, may be built up and then deposited upon the river bed at the edge of the water without the use of a float. In this apparatus I use a set of skids 33, which are suitably spaced from each other and their inner ends rest upon the embankment, while their outer ends project out over the water, and they are connected at their outer ends each with a supporting cable 35, the other end of which is made fast to a fixed point 36, on the shore. When the skids are placed in this position, an apron 37, is laid across the skids and constitutes a platform upon which the slab 5, is then built. When a slab is completed, the sustaining cables 35, are slowly let out so as to lower their outer ends into the water and until they rest upon the bed of the river. Then these cables being released, the skids are in turn withdrawn by means of suitable tackle comprising a hook 38, and a cable 39, which is connected with a windlass 40, which is made fast to a convenient point on the shore. When the skids are thus withdrawn, the apron or shield 37, then rests upon the river bed with the slab 5, upon the apron. Then the hook 38, is connected with the apron by means of the perforation 41 therein, and the apron is gradually withdrawn from beneath the slab, thus leaving it directly upon the river bed.

Each skid at its inner end is formed with a socket or perforation 42, through which a long pin 43, is driven into the ground to temporarily hold the end of the skid in place. When the skids are to be removed, the pins 43, are removed and a hook 38, is inserted in the socket 42.

From the foregoing description it will be readily understood that by my improved method large areas of ground can be covered with this particular lining or revetment and can be made continuous in one direction and without joints between the

individual slabs, if desired. It will also be noted that steep inclines, as well as level surfaces, may be economically provided with this particular revetment, without necessitating the use of any of the usual forms. 70

My improvements, while particularly applicable to the waterside slope of a river or other body of water, may be used in other places with great advantage. For example, it may be used in roadway construction, and 75 in such use the metal folds may appear on the surface and thereby serve as a protective means for the cemental material and prevent trituration caused by the wheels of vehicles on the roadway, or by floating ice 80 and logs.

As above stated, I prefer to use wire-netting having a triangular mesh instead of a rectangular mesh, one reason for this preference being that the triangular mesh contains a multiplicity of elements which are brought into effective service. Referring, for example, to Fig. 3, in which there is shown the bent wire-netting having the triangular mesh, the long member 7^a, of the 90 bend, which may be considered as one foot in length, contains groups of polygons of six triangular elements, which triangles are indicated at a, b, c, d, e, and f, which elements are under tension when the stretch of 95 netting is under stress. In the short member 7^b, of the bend, which is about one third the length of the long member, there are also a multiplicity of elements, which by reason of their diagonal disposition act 100 as compression and tension members, when this member is subjected to a vertical strain, as will be understood particularly from Figs. 2 and 3. One of the important advantages of using my peculiar form of corrugated netting is that it restores itself to normal shape after being bent in sliding the slab into place from an incline. 105

I wish to be understood as not limiting my invention to the particular construction of the various different parts as herein shown, as it is evident that modifications may be made in the several different parts without, however, departing from the spirit of my invention. 110

My improvements are particularly well adapted for coverings for protecting river embankments and subaqueous surfaces from erosion. The plastic slabs which I have installed on river-beds are now as firm as rock bed and show no signs of deterioration after a long period of use beneath the water. It is also an advantage in some cases to make a continuous slab of great area and this I can readily do by the method 120 and means herein set forth, and without weakening the structure in any way. 125

By virtue of the reinforcement being shaped in the peculiar manner set forth, I am enabled to safely transfer the plastic 130

slab to the place where it is to be deposited and to bend the slab without liability of the reinforcement breaking or buckling and protruding through the slab. This is important as it prevents the slab from being disrupted or mutilated while being laid in place and this is particularly advantageous in subaqueous work. It will also be noted that while I lay the slab when in very plastic and flexible condition, nevertheless the water in which it is submerged does not in any way affect its integrity or tend to disintegrate the structure.

Having thus described my invention, what I claim and desire to secure by Letters Patent is:

1. In apparatus for laying a protective covering upon the surface to be protected, the combination of a reciprocating apron for receiving and supporting the covering, a suitable support for said apron, means for sliding said apron and projecting it with its superimposed covering toward the surface upon which the covering is to be deposited, and means for drawing back the apron from beneath the covering and gradually depositing the same on said surface.

2. In apparatus for laying a protective covering upon the surface to be protected, the combination of a movable flexible apron for receiving and supporting the covering and a suitable support for said apron, means for moving said apron with its superimposed covering to deposit the same on the surface to be protected, and means for drawing back the apron from beneath the covering and gradually depositing the same on said surface.

3. In apparatus for laying a protective covering upon the surface to be protected, the combination of a sliding apron for receiving and supporting the covering, a suitable support for said apron, means for sliding said apron and projecting it with its superimposed covering toward the surface upon which the covering is to be deposited, and means for drawing back the apron partly from beneath the covering and then withdrawing the apron-support and apron together so as to gradually deposit the covering on said surface.

4. In apparatus for laying a protective covering upon the surface to be protected, the combination of a reciprocating apron for receiving and supporting the covering, a suitable support for said apron, lateral guides for the apron, means for sliding said apron and projecting it with its superimposed covering toward the surface upon which the covering is to be deposited, and means for drawing back the apron from beneath the covering and gradually depositing the same on said surface.

5. In apparatus for laying a protective covering upon the surface to be protected, the combination of a reciprocating apron for receiving and supporting the covering, a suitable support for said apron, means for sliding said apron and projecting it with its superimposed covering toward the surface upon which the covering is to be deposited, and means for drawing back the apron partly from beneath the covering and gradually depositing it on said surface for the construction of a second unit covering to be attached to the rear end of said first mentioned unit, thus providing for a continuous covering of indefinite length.

6. In apparatus for laying a protective covering upon the surface to be protected, the combination of a movable platform or support, traveling mechanism mounted on said platform and having relative movement thereon, and adapted to have constructed directly on said mechanism a flexible plastic reinforced protective covering, means for causing said mechanism to travel forwardly with the superimposed covering thereon and directing the same toward the surface on which the covering is to be deposited and depositing the forward part upon said surface for the construction of a second unit covering to be attached to the first unit thus providing for a continuous covering of indefinite length.

In testimony whereof, I have hereunto set my hand in the presence of the two subscribing witnesses.

ALEXANDER CRAWFORD CHENOWETH.
